Ralph W. Crawford and Herman G. Fisher, East Aurora, N. Y., assignors to Fisher-Price Toys, Inc., East Aurora, N. Y.

Application June 24, 1952, Serial No. 20,338

Term of patent 14 years

(Cl. D34—15)

To all whom it may concern:

Be it known that we, Ralph W. Crawford and Herman G. Fisher, citizens of the United States, residing at 512 Ridge Avenue, East Aurora, New York, and 861 Chestnut Hill Road, East Aurora, New York, respectively, in the county of Erie and State of New York, have invented a new, original, and ornamental Design for a Trundle Toy, of which the following is a specification, reference being had to the accompanying drawing, forming part thereof.

Fig. 1 is a top plan view of a trundle toy showing our design;

Fig. 2 is a side elevational view thereof;

Fig. 3 is a bottom plan view thereof;

Fig. 4 is a front end elevational view thereof; and

Fig. 5 is a rear end elevational view thereof.

We claim:

The ornamental design for a trundle toy, as shown and described.

RALPH W. CRAWFORD.
HERMAN G. FISHER.
